Gooding Holloway of Miamisburg Ohio
Letters Patent

The Schedule contained in the Letters Patent and making part of the same containing a description in the words of the said Gooding Holloway himself of his improvement in the machine for making and pressing Bricks from moist or untempered clay.

To all to whom these presents shall come. Be it known that I, Gooding Holloway of the Town of Miamisburg, in the County of Montgomery and State of Ohio have invented a new and useful machine, including the frame and ground work supporting the same for making and pressing Bricks, from moist or untempered clay, and that the following is a full and exact description thereof of as follows upon the foundation and frame for working four moulds, abreast (but may vary in dimensions according to the number of moulds to be used).

The ground or main sills to be 18 by 2.11 in sq. The longest or side ones, 22 ft. and the end or short ones 14 ft. in length, with a suitable number of licks, or girders, to hold them firmly in place the working place 7 ft. 9 in long to be framed into the middle or middle sills and the end or back sills 8 inches sq for the purpose of receiving the feet of the joint boxes. The main sills will meet where the boxes are placed, may be 3.2. feet long in order to avoid a frame to cross the main working wheel 10 ft. of it reducible to 8 in sq. On each end of the front sills stands a post 6 by 8 in sq. extending into the plate above into which are framed two more pieces two feet apart under the boxes over 18 in above the sills for holding the clamps to confine the piston or condensing bars in their places of perpendicular action as hump upon the ends of the long boxes. Immediately behind or 4 in. from the front sills are placed two main posts 18 in sq. & 10 1/3 feet high from the top of the sills to the under side of the plate (which plate should be 8 in. sq. and corresponding length of the sills) mortised through the main sills and let in with dove tail tenons well pinned, and also secured by strong iron spikes passing under the sills, and bolted

378.

through the first 12 in above the bottom. Into these posts are framed two main beams. The upper one 18 by 24 in sq, and the lower one 18 by 12 in with double tenons. They are to be placed 21 in apart and the lower one 3 ft. above the main sill, let in with a notch of 3 in to the posts, and between them are to be placed 8 pieces or uprights 1 ft wide and 3 in thick framed in by mortises for the purpose of hanging and confining the main or long beams. On the top of the upper beam are placed 14 short posts, on which hang the discharging laves, 3 ft 8 in in gear of the forward main posts, are placed two more posts 8 in square, of same height as the others, which come over certain distance more than with uprights, same in number as the forward ones but left one longer, 2 by 6 in sq and 2 ft 9 in long, to serve as guides for the back ends of the main beams. 5 ft. 3 in behind the last named or middle posts on the right hand side, is to stand another 12 in sq. of equal height to receive the end of the shaft on which the laves are fixed, and on the opposite side next the main wheel are placed two other posts in this side 3 $\frac{1}{2}$ ft apart of like dimensions, into which are let in slipped two 2 sq ft pieces 3 ft long and of suitable size to receive the end of the main wheel and spur wheel shafts. The former to be 14 $\frac{1}{2}$ ft. from the top of the sill to the center of the shaft. Immediately in front of the rear main post that contains the main wheel shaft is placed a piece of timber 8 in wide, into this are let 4 posts 6 ft high, in the top of which hang the short main beams by means of connecting rods. Into the upper end of the main or rear main post and the opposite post is inserted a beam or cap piece to which are attached the longitudinal connecting bars of the double beam rods, connected with the joint bars. That part of the frame containing the main driving wheel is connected with the post already described and should be of corresponding dimensions. The main cog wheel to be 14 ft. in diameter placed near the top of its vertical shaft of 24 inches diameter, to be moved or propelled by animal or steam power. Therefore by inclined planes or at the end of a horizontal bar 14 ft. from the shaft and 2 ft from its base. Into the main cog wheel plays a spur wheel 21 inches di-

smoke placed on the end of a shaft 8 ft. long, at the other end is another smoke wheel of same size playing into a wheel 6 ft. diameter which turns a shaft whereon is placed a frame that covers the joint and main lever or, as we call it, the frame for working the discharging lever. This aforesaid frame may be made of a rod strapped with iron, or wholly of cast iron 2 $\frac{1}{2}$ feet in length from the centre of the shaft on which they are placed to the point or end of the frame in shape of letter D. The small bars to oppose to the discharging lever, should be 1 $\frac{1}{2}$ inch in length and $\frac{1}{4}$ the distance around the shaft for the purpose of raising and holding up the frame sufficient time for removal. The first mentioned frame, which more the joints and long lever, not between the iron rods attached to the joint of the joint lever by means of a bolt passing through the whole of them. So the other end of these rods is placed a friction roller against which the frame slides in moving round. The rods are attached to the end of the main working bar, and hung at the upper end by a bolt or hinge. The lower part of the joint lever is 5 ft. long and the upper part 2 ft. 9 inches each measuring from the centre of the joint. The upper end is connected by means of a joint to the end of the long lever working under it. The lower end of the joint lever is hung by and plays on a bolt passing through it and the long piece in which the foot rest is.

The main lever is 12 ft long and 10 $\frac{1}{2}$ in thick and 16 in at the widest part when it is hung by a 2 in iron bolt playing in a iron box within 2 $\frac{1}{2}$ ft. of the forward end and tapering to 10 $\frac{1}{2}$ in at the other. The condensing air passing from it is applied by means of a piston bar of iron of suitable size to enter the mould at the lower end, which is to be faced with iron or steel polished entirely smooth. The upper part of the bar to be sufficiently wide to hang upon the end of the other main lever by means made round on the under side and is confined to it, suspended in action by the means before mentioned. The blocks when pressed are raised out of the mould by means of the discharging lever (working above the main lever) which are moved by the small bars acting upon the short

brace, connected by a rod with the said discharging lever, 11 $\frac{1}{2}$ feet in length and hung 9 $\frac{1}{2}$ ft. from the front end whereto it is 6 in. wide and 2 in. thick tapering to a square, same as the long bars. On the front end is, being a stirrup or bail at each end of which a small rod, 105 in. apart are attached reaching down through the main front sill on each side of the mould and through each end of a cross bar of iron or timber, on the centre of which stands a short post or stem for the purpose of lifting up the brick to the top of the mould, fastened by nuts or screws on the end of the rods. The short lever connected by a rod with the discharging lever is 1 ft. 3 in. long & 3 by 2 in. wide and is hung 12 in. from the end of the same. The lower part of the moulds, are connected by rods, 6 ft. 8 in. long. The moulds which are to be set into the main front sill may be cast whole, or in 4 pieces and put together by screws. The latter form is preferable, on account of polishing the inside more perfectly smooth which is essentially necessary. The top may be half an inch concave for the purpose of pressing the bricks more solid at the edge. The lower or bottom part to be a plate of iron or steel, filled and fastened upon a block of wood to give the mould a close & possibly considerable with its movement, to the centre of which is also attached the stem passing down through the sill and fastened to the bottom of the aforesaid moving stirrup for raising the brick out of the mould, as previously described. A screen of the same size of pulsed iron, sifted and having the clay is made of wire No. 10, 3 $\frac{1}{2}$ feet diameter and left long fastened upon a reel with bands of steel iron on each end of 4 inches wide, and a second one 12 in. in front of the first, one foot in width for the purpose of protecting that part of the screen where the clay is, the screen. The wheel to be iron & by a band or the passing round a wheel upon the front wheel shaft & also round a wheel fastened upon the shaft of the reel placed so near the moulds that one end of a good ground may be let into part of the main front posts and the other into a small iron or plate for the purpose of supporting the same. What I claim is my own in

4/21/1836 9605X

381

vention and not previously known in the above described machine and its ground work is in the first place the general construction of the frame supporting and containing the whole machinery. Secondly I claim the ^{use of} application of the joint lever, to the end of the long or main lever, whereby superior power is obtained. Also the bar, or double cam rocker, through which the cam moves, likewise the friction roller as fixed in the end of this cam against which the cam strikes when moving round. Also the suspending bar and the way and manner they are attached to the frame body.

Also the application of the long and short discharging lever with the manner of hanging and connecting the same. The stirrup also is, being by a stirrup upon the end of the discharging lever for the purpose of raising the brick out of the moulds as also the small bars before described. I further claim the improved construction, form, size and prospecting of the bar, and in connection the combined application and operation of the three different powers or principles embodied in and by the frame, joint lever and main long lever, any two of them to be used or worked by an animal or hand, picture drawing machine, for one or more moulds, for the several purposes of making and preserving bricks from moist or unprepared clay.
